UNITED STATES PATENT OFFICE

151,031

DESIGN FOR A BROOCH OR THE LIKE

Augustus Casciano, Providence, R. I., assignor to R. M. Jordan & Company, Inc., a corporation of Rhode Island

Application December 31, 1947, Serial No. 143,469

Term of patent 3½ years

(Cl. D45—19)

To all whom it may concern:

Be it known that I, Augustus Casciano, a citizen of the United States, residing at Providence, in the county of Providence and State of Rhode Island, have invented a new, original, and ornamental Design for a Brooch or the like, of which the following is a specification, reference being had to the accompanying drawing, constituting a part thereof.

Fig. 1 is a front elevation of a brooch or the like, showing my novel design; and

Fig. 2 is a side view thereof.

I claim:

The ornamental design for a brooch or the like, substantially as shown.

AUGUSTUS CASCIANO.
